CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing a first embodiment of our new design, shown in color; and,

FIG. 2 is a front view of a display screen or portion thereof with graphical user interface showing another embodiment of our new design, shown in color.

In FIGS. 1 and 2, the color(s) shown form a part of the claimed design. These Figures are intended to be directed to the actual colors depicted.

The dashed broken lines illustrate portions of the graphical user interface and form no part of the claimed design. The dashed-dotted broken lines illustrate a display screen or portion thereof and form no part of the claimed design.
